(57) CLAIM

The ornamental design for a culinary knife maintenance and sharpening steel, as shown and described.

DESCRIPTION

FIG. 1 is a front perspective view of the novel culinary knife maintenance and sharpening steel;

FIG. 2 is a top plan view thereof;

FIG. 3 is a fragmentary front elevation view of the handle portion of the culinary knife maintenance and sharpening steel, wherein the rear elevation view is identical;

FIG. 4 is a fragmentary left side elevation view of the handle portion of the culinary knife maintenance and sharpening steel, wherein the right side elevation view is identical; and,

FIG. 5 is a bottom plan view thereof.
